GAME BOARD

Richard H. McCormic, Many, La.

Application July 21, 1958, Serial No. 51,864

Term of patent 14 years

(Cl. D34—5)

Fig. 1

Fig. 2

Fig. 3

Figure 1 is a plan view showing my new design; Figure 2 is an edge elevational view thereof; and Figure 3 is a fragmentary top plan view of a portion of the game board and on an enlarged scale.

I claim:

The ornamental design for a game board, as shown.
